OPERATING MECHANISM FOR PUNCH PRESSES

James MacBlane, Elmira Heights, N. Y., assignor to Bendix Aviation Corporation, South Bend, Ind., a corporation of Delaware

Application October 6, 1939, Serial No. 298,284

3 Claims.

(Cl. 74—2)

The present invention relates to operating mechanism for punch presses or the like and more particularly to a non-repeating trip actuating device for the drive clutches of power presses.

In applicant's prior application Serial Number 209,751, filed May 24, 1938, there is disclosed a control system for punch presses so arranged as to insure that both hands of the operator are in positions of safety before the press can be actuated. This is accomplished by actuating the clutch tripping mechanism by means of a solenoid controlled by two push buttons in series, which buttons are located at a safe distance away from the press ram.

The present invention relates particularly to an improved form of connection between the solenoid and the clutch tripping mechanism whereby a single operation of the press is assured at each energization of the solenoid irrespective of the length of time the energization of the solenoid is maintained.

It is an object of the present invention to provide a novel operating mechanism for punch presses which is efficient and reliable in operation and simple and economical in construction.

It is another object to provide such a device which is quickly and easily adjustable to regulate the stroke of the trip device.

It is a further object to provide such a device which is not subject to wear or loss of adjustment over long periods of use.

It is another object to provide such a device which may be quickly and easily adapted for continuous operation of the press, if desired, so long as the hands of the operator are in positions of safety.

It is another object to provide such a device which is positive in action and rigid in construction so as to introduce no lost motion into the linkage which operates the trip mechanism for the press.

It is another object to provide such a device which is self-aligning in action and imposes no side thrusts or bending moments on the mechanism.

It is another object to provide such a device which by reason of its unitary construction may constitute in effect a part of the clutch trip link of the press and is accordingly readily applicable to all types of presses.

It is another object to provide such a device which does not slow up the operation of the press or interfere with the production thereof in any way.

Further objects and advantages will be apparent from the following description taken in connection with the accompanying drawing in which:

5 Fig. 1 is a side elevation partly broken away and in section of a preferred embodiment of the invention showing the parts in idle position; and

10 Fig. 2 is a similar view showing the parts in the positions assumed during energization of the actuating solenoid, after release of the press trip link.

In Fig. 1 of the drawing there is illustrated a housing or box 1 of any suitable type which may be mounted in any convenient position on the

15 frame of a punch press, not illustrated. A solenoid actuating device indicated generally by numeral 2 is mounted within the housing 1 in any suitable manner and comprises a coil 3 and an armature 4 actuated thereby. A trip link for the control clutch of the press is illustrated fragmentarily at 5, and is arranged to be actuated by the armature 4 of the solenoid upon energization of the coil 3. For this purpose the link 5 is provided with a cylindrical terminal portion 6 which may, as illustrated, be in the form of an extension adjustably connected thereto and slidably mounted in telescoping relation within a cylindrical socket 7 formed in the upper end of a plunger or slide 8. The lower end of the plunger is reduced in diameter as indicated at 9, forming a shoulder 11, and is pivotally connected as indicated at 12 to the armature 4.

The extension 6 of link 5 is provided with an annular recess or groove 13, and the socket 7 of plunger 8 is provided with one or more recesses or openings 14 adapted to register with the recess 13 in the link extension 6 when the members 6 and 7 are fully telescoped. Means are provided for coupling these members together in such fully telescoped position in the form of balls 15 loosely fitting in the openings 14 and arranged to project and fit in the recess 13.

45 Locking means are provided for confining the balls 15 in coupling position in the form of a sleeve 16 slidably mounted on the exterior of the socket 7 of plunger 8 and having an annular recess 17 adapted to loosely fit over the projecting portions of balls 15, and providing an inclined shoulder 18 adapted to engage such balls and 50 wedge them in coupling position.

An annular recess 19 is formed in the interior of sleeve 16 adjacent the recess 17, recess 19 being sufficiently deep so that when it is brought into registry with the balls 15, the balls are free to 55 move out of the recess 13 in extension 6 of the

trip link, thereby permitting uncoupling of the link and plunger.

The sleeve 16 is urged toward its locking position as shown in Fig. 1 by gravity when the parts are arranged vertically and also, if desired, by yielding means such as a spring 21 bearing at one end against the sleeve and at its other end against a shoulder 22 on the upper end of the plunger 8. Means for causing the sleeve 16 to release the balls 15 is provided comprising an abutment member in the form of an extension or skirt on the sleeve and here shown as a hollow cylinder 23, the upper portion of which is slotted as indicated at 24 and clamped as shown at 25 on the exterior of the sleeve. The skirt 23 extends below the body portion of sleeve 16 into juxtaposition with an abutment member such as a washer 26 surrounding the reduced portion 9 of the plunger 8 and resting on the housing 1. When the skirt 23 engages the abutment member 26, downward motion of the sleeve 16 is arrested, and further motion of the plunger 8 brings the balls 15 into registry with the recess 19 in the sleeve whereby the balls are permitted to move radially out of the recess 13 of the link extension 6 and the latter is freed and allowed to return to its idle position, as illustrated in Fig. 2. It will be understood that skirt 23 may be formed as a part of sleeve 16, but it is preferred to mount the skirt adjustably on the sleeve 16 in order to permit adjustment of the stroke of the trip link 5.

Means for returning the plunger 8 and its associated parts to idle position is provided in the form of a spring 27 bearing at its lower end against the abutment member 26 and at its upper end against the shoulder 11 of plunger 8.

In the operation of the device, energization of the solenoid 3 by any suitable means, not illustrated, under the control of the operator causes the armature 4 to pull down the plunger 8 from the position shown in Fig. 1 to the position shown in Fig. 2. The initial motion of plunger 8 is transmitted through balls 15 to the extension 6 of link 5 to actuate the tripping mechanism, not shown, of the press. When the skirt 23 of sleeve 16 engages the abutment member 26, downward movement of the sleeve is arrested, whereupon further downward movement of plunger 8 carries the balls 15 into registry with recess 19, thus freeing the link 5 which returns to its idle position by virtue of the usual return spring for the punch press trip link, not illustrated. The press is thus caused to be actuated through one cycle and is then maintained inoperative so long as the solenoid 3 remains energized.

When the solenoid is deenergized, the plunger 8 and its associated parts are returned to their idle positions, as illustrated in Fig. 1, by means of the spring 27, the balls 15 being forced into the recess 13 of the link extension 6 by the inclined shoulder 18 of sleeve 16 when the balls come into registry with said recess.

If, for any reason, it should be desired to operate the press continuously so long as the solenoid 3 is energized, it is merely necessary to loosen the clamp 25 and move the skirt 23 upwardly on the sleeve 16 until the skirt will not engage the abutment member 26. The coupling then acts as a solid connection and holds the trip link 5 down so long as the solenoid 3 is energized.

It has been found desirable to relieve the upper edge of the recess 13 in the link extension 6 as shown at 28 so that any slight upsetting of the metal due to the tapping of the balls

against said extension upon re-engagement thereof, will not roughen the cylindrical bearing surface of the extension within the socket 7.

Although but one embodiment of the invention has been shown and described in detail, it will be understood that other embodiments are possible and various changes may be made in the design and arrangement of the parts without departing from the spirit of the invention as defined in the claims appended hereto.

What is claimed is:

1. In a trip operating mechanism for power presses and the like, a housing, a plunger slidably mounted therein, a trip actuating link telescoped within the plunger having a peripheral recess, the plunger having an opening adapted to register with the recess, a coupling ball in the opening normally extending into the recess to thereby hold the link in the plunger, a sleeve slidably mounted on the plunger having an inclined shoulder normally engaging the exterior of the coupling ball to wedge it in said recess and lock the sleeve, plunger and link for longitudinal movement in unison, said housing serving as a stop to arrest the movement of the sleeve at a predetermined point in its longitudinal movement and thereby free the coupling ball and release the link, yielding means on the plunger urging the sleeve toward locking position, means for applying traction to the plunger, and yielding means for returning the plunger to idle position.

2. In a trip operating mechanism for presses or the like, a slideable plunger having a hollow cylindrical extension with a radial opening therethrough, a trip actuating link slideably telescoped in the plunger having an annular recess, a ball seated in said opening and adapted to enter the recess when in registry therewith, a sleeve slideably mounted on said extension having an internal inclined shoulder adapted to engage the ball and wedge it into the recess, locking the link, plunger and sleeve for longitudinal movement in unison, and an annular recess adjacent the shoulder, yielding means on said extension engaging the sleeve to press the shoulder against the ball, and an abutment engageable by the sleeve at the end of the stroke of the trip link to permit the ball to enter the recess in the sleeve and uncouple the link from the plunger.

3. In a trip operating mechanism for power presses and the like, a housing, a plunger slidably mounted therein and extending therefrom, yielding means drawing the plunger out of the housing, a trip actuating link telescoped within the plunger having a peripheral recess, the plunger having an opening adapted to register with the recess, a coupling ball in the opening normally extending into the recess to thereby hold the link in the plunger, a sleeve slidably mounted on the plunger having an inclined shoulder normally engaging the exterior of the coupling ball to wedge it in said recess and lock the sleeve, plunger and link for longitudinal movement in unison, yielding means between the plunger and sleeve urging the sleeve into locking position, and a skirt mounted on the sleeve and extending toward the housing, said skirt being adjustable longitudinally on the sleeve to engage the housing at a predetermined point in the travel of the sleeve to thereby uncouple the link from the plunger.
